(57) **CLAIM**

The ornamental design for a bird exclusion device, as shown and described.

DESCRIPTION

FIG. 1 is a top perspective view of a bird exclusion device in accordance with a first embodiment of the invention; FIG. 2 is a bottom perspective view of the bird exclusion device of FIG. 1;

FIG. 3 is a right side view of the bird exclusion device of FIG. 1;

FIG. 4 is a left side view of the bird exclusion device of FIG. 1;

FIG. 5 is a front view of the bird exclusion device of FIG. 1;

FIG. 6 is a rear view of the bird exclusion device of FIG. 1;

FIG. 7 is a bottom view of the bird exclusion device of FIG. 1;

FIG. 8 is a top view of the bird exclusion device of FIG. 1;

FIG. 9 is a top perspective view of a bird exclusion device in accordance with a second embodiment of the invention;

FIG. 10 is a bottom perspective view of the bird exclusion device of FIG. 9;

FIG. 11 is a right side view of the bird exclusion device of FIG. 9;

FIG. 12 is a left side view of the bird exclusion device of FIG. 9;

FIG. 13 is a front view of the bird exclusion device of FIG. 9;

FIG. 14 is a rear view of the bird exclusion device of FIG. 9;

FIG. 15 is a bottom view of the bird exclusion device of FIG. 9; and,

FIG. 16 is a top view of the bird exclusion device of FIG. 9.

The broken lines depict environmental structure and are for illustrative purposes only and form no part of the claimed design.
